UNITED STATES PATENT OFFICE

2,140,302

SHOE

Edward F. Roberts, Rye, N. Y., assignor, by mesne assignments, to United States Rubber Company, New York, N. Y., a corporation of New Jersey

Application July 18, 1936, Serial No. 91,417

1 Claim. (Cl. 36—51)

This invention relates to shoes and more particularly to ladies' or misses' low shoes of the step-in or pump type.

Such low shoes depend largely upon the pressure they exert across the top fore part of the foot to retain the shoe snugly in place upon the foot and to prevent the shoe from sliding up and down at the heel. As a result, most shoes of the step-in or pump type either exert an uncomfortable binding pressure across the top of the foot, or fit the foot so loosely that the shoe tends to bulge at the sides of the foot and slide up and down on the heel.

It has been proposed heretofore to provide elastic inserts or gores in various parts of shoes to impart elastic properties to such portions of the shoes but such attempts heretofore have not been entirely satisfactory. One difficulty with such proposed prior constructions has been due to the fact that if the elastic insert exerts a strong contractive force, this contractive pressure upon the foot is uncomfortable, and if the elastic insert does not exert a strong contractive force it will stretch too freely under the movements of the foot in the shoe.

Another difficulty experienced heretofore in using elastic inserts and gores in shoes has been due to the fact that if the elastic insert or gore extends to the upper edge of the shoe no way was known of imparting a neat, durable and satisfactory finish to such elastic upper edge without interfering with the stretch of such elastic insert at this upper edge.

The present invention seeks to overcome these difficulties and one important feature of the invention resides in a construction for rendering elastic a small area at the throat of the shoe to thereby relieve the binding pressure of this portion of the shoe upon the foot, without providing a sufficiently large elastic area to permit this portion of the shoe to either contract or expand more than a small amount from the desired size and shape of the finished shoe. Another important feature resides in a construction for providing a slight contractive force at the upper edge of the shoe around the entire or substantially entire foot-receiving opening so that this contractive force will tend to reduce slightly the size of the foot-receiving opening to thereby improve the fit of the shoe and cause the upper edge of the shoe to lie close to the sides of the foot.

The above and other features of the invention will be more fully understood from the following description when read in connection with the

accompanying drawing illustrating good practical forms thereof, and wherein:

Fig. 1 is a side elevation of a ladies' pump embodying the features of the present invention;

Fig. 2 is a front view of the shoe of Fig. 1; 5

Fig. 3 is an enlarged section taken on the line 3—3 of Fig. 2;

Fig. 4 is a similar section taken on the lines 4—4 of Fig. 1; and

Fig. 5 is a side elevation of a relative high step- 10 in type of shoe embodying the features of the present invention.

Referring first to Figs. 1 and 2 of the drawing, the shoe here shown is a pump, which for the most part may be of well known construction, and 15 comprises the shoe sole 10, heel 11 and upper 12, and the upper may have its outer material formed of leather or cloth as heretofore.

In order to render a portion of the shoe at the throat area elastic so as to relieve the uncomfortable or binding pressure which pumps frequently exert across the top of the foot, this throat area is formed of fine closely woven elastic fabric 13 which fabric is preferably so constructed that it will require a relatively strong pull to stretch 25 the same. The fabric 13 may be formed of inelastic yarn, and elastic yarn such as disclosed in the Adamson Patent No. 1,822,847 granted September 8, 1931, and the elastic yarn may constitute either the warp or the weft and is tightly 30 interwoven with the non-elastic yarn to provide a strong, one-way stretch fabric. This elastic fabric is preferably so positioned in the shoe that the elastic yarns 14 extend crosswise of the shoe, that is at right angles to the longitudinal axis of the 35 shoe as shown. The shoe of Fig. 1 may have its throat area rendered elastic by simply cutting away the portion of the shoe upper 12 adjacent the throat of the shoe and securing in place thereof the woven elastic fabric 13 which may be sewed 40 to the shoe upper 12 by the row of stitching 15.

The size and shape of the elastic area 13 may obviously be varied as desired but this area is preferably relatively small to thereby prevent this portion of the shoe from being stretched more 45 than a small amount from the finished shape which is to be imparted to the shoe. This small elastic area 13 will serve to relieve the uncomfortable pressure at the throat of the shoe upon the foot and will also increase the snug fit of the 50 shoe to thereby improve its appearance and prevent the shoe from slipping up and down upon the heel of the wearer.

It is important to provide the elastic fabric 13 at its upper edge with a smooth rounded bead 55

or edge which will be durable and pleasing in appearance, and which at the same time will not interfere with the stretch of the elastic fabric 13. This is accomplished in accordance with the present invention by providing the upper edge of the fabric 13 of the shoe with an elastic binding 16 which is preferably formed of a thin narrow strip of woven material having the elastic threads 17 extending longitudinally thereof. These threads 17 are preferably quite small and may be formed in accordance with the disclosure of the Adamson patent above referred to. The binding 16 is secured to the upper edge of the elastic fabric 13 so as to form a rounded finishing bead. This is accomplished by turning in one edge of the binding 16 and securing this edge to the outer face of the fabric 13 near the upper edge thereof by a row of stitching 18 so that this edge of the binding is concealed at the outer face of the shoe, as will be apparent from Fig. 3. The remaining portion of the binding 16 is turned over the upper edge of the elastic fabric 13 to form the desired beaded edge and is secured in place against the inner face of the fabric 13 by a second row of stitches 19.

It is found desirable to provide this elastic finishing bead not only along the upper edge of the elastic fabric 13 but also along the upper edge of the entire or substantially entire foot-receiving opening of the shoe. The elastic binding 16 is therefore shown in Figs. 1 and 2 as extending entirely around the foot-receiving opening. The manner in which the binding 16 is secured to the upper edge of the non-elastic portion of the shoe will be apparent from Fig. 4 wherein the turned-in edge of the binding 16 is secured against the outer face of the shoe 12 by the row of stitches 18. The inner face of the leather or other material 12 forming the outer portion of the shoe upper is shown as provided along this upper inner edge with the usual non-elastic strengthening tape 20 which is adhesively secured to this portion of the shoe to prevent the material 12 from stretching along the upper edge of the foot-receiving opening. This shoe may be provided with the usual lining 21 which may be formed of thin leather or woven material, as desired, and after the binding 16 has been folded over the upper edge of the outer material 12 of the shoe, its remaining edge may be confined between the tape 20 and inner lining 21 as shown and may be secured in place therebetween by the row of stitches 19.

The binding 16 is formed of fine elastic webbing which will stretch easily and is preferably

55

secured in place along the upper edge of the shoe under slight tension so that it will exert a slight contractive force around the foot-receiving opening of the shoe. The effect of this is to tend to decrease the size of this opening 5 slightly. This causes the upper edge of the shoe to fit more snugly and serves also to hold the upper edge of the shoe against the sides of the foot to keep the shoe from gapping at the sides.

The features of the present invention are well 10 adapted for use not only in pumps but in other types of shoes having a considerably higher throat, such as shown in Fig. 5 which more closely approaches the height of the so-called Oxford shoe. Although the shoe shown in Fig. 5 15 is comparatively high in the throat it may be slipped on and off the foot without requiring any opening in the throat area due to the stretch permitted by the elastic fabric 22 in this area. This fabric may be constructed of a woven elastic material 20 and secured in the shoe in the manner above described in connection with Figs. 1 and 2. The entire upper edge of the shoe of Fig. 5 is preferably provided with a finishing bead formed of a narrow strip of an elastic binding 25 16 the same as in Fig. 1.

It will be seen from the foregoing that the elastic webbing or binding 16 forms two distinct functions, one being to provide the upper edge of the shoe with a round finishing bead of pleasing appearance, and the other being to exert a contractive force along the edge of the shoe that serves to pull the sides of the shoe in towards the foot to prevent gapping at the sides.

Having thus described my invention, what I 35 claim and desire to protect by Letters Patent is:

A low shoe of the step-in or pump type adapted 40 to stretch slightly in the throat area, and including in its construction an upper having the throat portion thereof formed of elastic material, the upper edge of the shoe being provided in the elastic throat area and along each side of the shoe with a finishing bead formed of a narrow strip of elastic fabric binding made with rubber threads, one edge of the binding being 45 rolled under to conceal this edge at the outer face of the shoe and the other edge being secured inside the shoe, said binding being secured to the upper edge of the shoe under sufficient longitudinal tension to exert a contractive force across 50 the instep and at the sides of the shoe to thereby reduce the tendency of the shoe to gap at the sides of the foot.

EDWARD F. ROBERTS. 55
